UNITED STATES PATENT OFFICE

139,501

DESIGN FOR A RUBBER HEEL

Ray E. Sannar, Elyria, Ohio

Application October 5, 1944, Serial No. 115,637

Term of patent 14 years

(Cl. D7—5)

To all whom it may concern:

Be it known that I, Ray E. Sannar, a citizen of the United States, residing at Elyria, in the county of Lorain and State of Ohio, have invented a new, original, and ornamental Design for a Rubber Heel, of which the following is a specification, reference being had to the accompanying drawing, forming a part thereof.

In the drawing:

Fig. 1 is a plan view of a rubber heel showing my new design; and

Fig. 2 is a section taken on the line 2—2 of Fig. 1.

I claim:

The ornamental design for a rubber heel, substantially as shown.

RAY E. SANNAR.
